CLAIM

The ornamental design for an electronic table game, as shown and described.

DESCRIPTION

FIG. 1 is a perspective view of an electronic table game, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, solid lines illustrate the claimed ornamental design, whereas the broken lines illustrate unclaimed environmental features and form no part of the claimed design.

1 Claim, 7 Drawing Sheets
